UNITED STATES PATENT OFFICE

162,958

BRACKET FOR SUPPORTING KITCHEN
ARTICLES

Burton H. Ives, Chicago, Ill.

Application April 18, 1950, Serial No. 9,298

Term of patent 14 years

(Cl. D44—29)

To all whom it may concern:

Be it known that I, Burton H. Ives, a citizen of the United States, residing in the city of Chicago, county of Cook and State of Illinois, have invented a new, original, and ornamental Design for a Bracket for Supporting Kitchen Articles, of which the following is the specification, reference being made to the accompanying drawing, forming a part hereof.

Fig. 1 is a perspective view of a bracket for supporting kitchen articles, showing my new design;

Fig. 2 is a similar perspective view of the same taken at a different angle; and

Fig. 3 is a side elevational view of the same showing the manner in which the bracket may be attached to a kitchen cabinet door or wall.

The portion of a wall shown in broken lines is for illustrative purposes only.

I claim:

The ornamental design for a bracket for supporting kitchen articles, as shown and described.

BURTON H. IVES.
